UNITED STATES PATENT OFFICE.

HENRY SCHLEINKOFER, OF CLEVELAND, OHIO.

HAT-SHAPE BRACE.

1,262,852.

Specification of Letters Patent. Patented Apr. 16, 1918.

Application filed June 4, 1917. Serial No. 172,831.

To all whom it may concern:

Be it known that I, HENRY SCHLEINKOFER, a native-born citizen of the United States, residing at 1646 East 38th street, in the city of Cleveland, county of Cuyahoga, and State of Ohio, have invented a Hat-Shape Brace.

My invention relates to improvements in hat shape braces. The object of this invention is to provide a simple, inexpensive and durable means of rigidly holding and preventing a hat from caving inward toward the center either at the front or back portions of the crown. In order to accomplish the foregoing I provide a brace so designed that it will slip between the hat band and the crown of the hat. The brace is shaped to conform to the natural formation of the hat.

20 My invention is illustrated in the accompanying drawings, wherein:

Figure 1 shows the brace or support.

Fig. 2 shows the brace or support inserted in a hat.

25 Referring to Fig. 1, the brace or support A can be made of card-board, rubber, linen, celluloid or any pliable material. The material must be pliable enough so that it may be curved to fit the shape of the hat and is 30 preferably made of thin material so as not to inconvenience the wearer.

As shown, the brace A has the upper portion curved so as to form two projections 3 and 4 and a recess 2; while the lower portion, as shown at 4 is straight and arranged to slip between the hat band and the hat proper.

35 Referring to Fig. 2, it will be noted that a brace A is inserted at both the front and 40 forward portions of the hat. As shown, the type hat used is of soft material provided

with a recess 7 which conforms to the recess 2 of the brace, while the raised portions 5 and 6 of the hat conform to the raised portions 3 and 4 of the brace. When the braces 45 are inserted in the hat, as shown in Fig. 2, the outer surface bears against the inner surface of the hat and prevents it from becoming creased or bent, while the upper edge retains the form of the crease or indenta- 50 tion.

While I have shown a particular type hat and a support arranged to be used therewith, it naturally follows that braces can be formed to support any type of hat regard- 55 less of its shape.

I claim—

1. A device of the class described comprising a single flat piece of pliable material arranged to be inserted in the sweat band 60 of a hat for holding the hat in shape.

2. A device of the class described comprising a single flat piece of pliable material arranged to be inserted in the sweat band at either end of a hat, said piece of 65 material designed to conform to the shape of the hat.

3. A hat brace comprising a single piece of pliable material arranged to be inserted in the sweat band at either end of the hat; 70 said piece of material being designed to conform to and to retain the shape of the hat.

4. A hat brace comprising a single piece of pliable material arranged to be inserted in the sweat band at either end of the hat; 75 said piece of material, when so inserted, having one of its flat surfaces engaging the inner surface of the hat and its upper edge designed to conform with and engage the crown of the hat for retaining its shape. 80

HENRY SCHLEINKOFER.
